US00D800895S

(12) **United States Design Patent** (10) **Patent No.:** **US D800,895 S**
Prentice et al. (45) **Date of Patent:** **** Oct. 24, 2017**

(54) **FACE MASK CUSHION**

(71) Applicant: **Fisher & Paykel Healthcare Limited**,
Auckland (NZ)

(72) Inventors: **Craig Robert Prentice**, Auckland (NZ);
Bernard Tsz Lun Ip, Auckland (NZ);
Mark Aryind McLaren, Auckland (NZ);
Kyle Gregory Brown, Auckland (NZ);
Chris Onin Limpin Hipolito,
Auckland (NZ); **Mark Richard
Tomlinson**, Auckland (NZ); **Melissa
Catherine Bornholdt**, Auckland (NZ)

(73) Assignee: **Fisher & Paykel Healthcare Limited**,
Auckland (NZ)

(**) Term: **15 Years**

(21) Appl. No.: **29/540,684**

(22) Filed: **Sep. 25, 2015**

(51) LOC (10) Cl. **29-02**

(52) U.S. Cl.

USPC **D24/110.4**

(57) **CLAIM**

The ornamental design for a face mask cushion, as shown and described.

DESCRIPTION

FIG. 1 is a top, front and side perspective view of a first embodiment of a face mask cushion embodying our new design;

FIG. 2 is a top, rear and side perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and

FIG. 8 is a bottom view thereof.

FIG. 9 is a top, front and side perspective view of a second embodiment of a face mask cushion embodying our new design;

FIG. 10 is a top, rear and side perspective view thereof;

FIG. 11 is a front view thereof;

FIG. 12 is a rear view thereof;

FIG. 13 is a first side view thereof;

FIG. 14 is a second side view thereof;

FIG. 15 is a top view thereof; and,

FIG. 16 is a bottom view thereof.
